UNITED STATES PATENT OFFICE.

GEORGE BERNARD HANDLEY AND EDGAR GEOFFREY HANDLEY, OF BRADFORD,
ENGLAND.

ENDLESS CONE BELT.

Application filed May 6, 1926, Serial No. 107,188, and in Great Britain January 9, 1926.

The present invention relates to improvements in endless cone belts designed for use on the cone drums of the drawing and speed frames of textile spinning machinery. 5 These belts are now formed of two plies of leather, the outer ply of greater width than the inside ply. This belt construction reduces the actual frictional contact of the belt on the drum to a minimum while the 10 frictional ply is supported by a wider ply which takes up most of the pull of the load and at the same time compresses the narrow frictional ply on to the surface of the cone drum. The inside ply is made up of soft 15 and resilient leather which in use either compresses or extends while passing over the drums or between them, thus acting as a cushion and minimizing various torsional strains to which the belt is subjected owing 20 to the opposing planes of the cone drums. The outside ply is made of firm stretched leather adapted to resist tension and fork action.

Owing to the vertical drive and the consequent extreme tension to which the belts 25 are subjected and the high temperature of the textile spinning rooms, these belts become exceedingly hot in use and this heat quickly destroys the efficiency of the inside ply by 30 cracking the grain of the leather and ultimately breaking said ply. In the same period of use the leather of the outside ply remains in comparatively good condition except that the great tension on the belt and 35 the narrow width of the inside ply causes extreme frictional contact between the belt and the drums in a concentrated space which necessitates strong pressure from the belt fork (which is constantly in operation in 40 this type of spinning machinery) on one edge of the outside ply thus causing a quick reduction in the width of said outside ply on one side with the result that the belt is difficult to reline and repair in a satisfactory 45 manner.

The present invention is designed to provide means whereby the running temperature and fork pressure necessary for such a belt is greatly reduced by the provision of a 50 closely pitched series of elongated longitudinal slots cut about the axis of the inside ply, which slots form an air escape between the

surface of the drum and the belt, and thus reduce the heat generated by the frictional contact of the belt with the drums and also 55 reduce the rigidity of the inside ply in use and consequently increase the efficiency and durability of the belt.

Our invention is shown by way of example in the accompanying drawings, in 60 which—

Figure 1 shows a perspective view of the endless cone belt in position on a pair of cone drums,

Figure 2 shows a plan view on an enlarged 65 scale of a portion of the cone belt, and

Figure 3 shows a transverse section through Figure 2.

In the drawings, A indicates the inside 70 ply made up of soft resilient leather which in use compresses while passing over the surfaces of the drums B and extends when passing between said drums. C indicates the outside ply which is fastened to the inside ply A by the rivets D and is adapted 75 to resist the tension and fork action to which the belt is subjected.

The invention is carried into effect by providing a closely pitched series of elongated longitudinal slots E cut about the central 80 axis of the inside ply, as shown in the drawings. These slots extend right through the inside ply, but are not carried into the outside ply, with the result that the air reliefs formed by the slots between the surface of 85 the drum and the belt do not increase the liability of the belt to buckle in the centre owing to the edge pressure resulting from the fork action on the belt caused by the cone form of the drum.

These longitudinal slots also reduce the 90 rigidity of the inside ply and permit an easier adjustment of the belt to the varying torsional strains to which the belt is subjected in passing from one cone drum to 95 the other and consequently reduce the resistance of the fork action and thus lessen the wear on the edge of the outside ply.

What we claim is:—

An endless belt for cone pulleys comprising 100 an inside ply of soft resilient leather adapted to be compressed when passing over the surfaces of the pulleys and to extend when passing between said pulleys, an out-

side ply of firm stretched leather and of wider section than said inside ply adapted to support the inside ply and to resist the tension and fork action to which the belt is subjected and an air escape in the form of a closely pitched series of elongated longitudinal slots cut about the central axis of the

inside ply adapted to reduce the running temperature of the belt and the fork pressure necessary to move it.

In testimony whereof we have signed our names to this specification.

GEORGE BERNARD HANDLEY.
EDGAR GEOFFREY HANDLEY.
